UNITED STATES PATENT OFFICE.

GEORGE W. OVERALL, OF ~~MEMPHIS~~, TENNESSEE.

AUTOMATIC FAN.

SPECIFICATION forming part of Letters Patent No. 255,659, dated March 28, 1882.

Application filed October 24, 1881. (No model.)

To all whom it may concern:

Be it known that I, GEORGE W. OVERALL, of Memphis, in the county of Shelby and State of Tennessee, have invented certain new and useful Improvements in Automatic Fans; and I do hereby declare that the following is a full, clear, and exact description of the invention, which will enable others skilled in the art to which it appertains to make and use the same, reference being had to the accompanying drawings, which form a part of this specification, and in which—

Figure 1 is a detail view of the spring-motor and its attachments for operating the fan bar or shaft. Fig. 2 is a front elevation of part of the fan-bar with one of its fans, showing the motor in section. Fig. 3 is a cross-section of the fan-shaft, showing one of the fans and fan-clamps; and Fig. 4 is a perspective view of a bedstead, illustrating the application of my improved automatic fan.

Similar letters of reference indicate corresponding parts in all the figures.

My invention has relation to automatic fans, or fans operated by a train of clock-work and adapted to be arranged in juxtaposition to a bedstead, dining-room table, chair, or hammock for the purpose of fanning the occupant, cooling off the air, and driving away flies and mosquitoes; and it consists in the combination of the motor, fan-shaft, fans, and standard or frame for supporting the apparatus, as hereinafter more fully set forth.

The frame or standard consists of two posts or uprights, A A, having cross-heads *a* at their lower ends, forming feet. The standards are connected at their upper ends by the fan-shaft B, at opposite ends of which are sleeves or thimbles C C, which slide upon posts A, and may be retained in any given position by means of set-screws D D.

Upon the fan-shaft B are two or more slides, E E, each one of which has a socket, E', into which is inserted a set-screw, *e*, and also a set-screw, *f*, inserted through the back part, which works against the fan-shaft B, so that by tightening the latter the sleeve may be fastened in any given position upon the shaft.

F F are the fans, the stems F' of which are inserted through the sockets E', and held in place therein adjustably by means of the set-screws *e*. The stems F' have universal joints *i*, by means of which the angle of the fan may be adjusted to any desired position, and when so adjusted be held in place by a set-screw, *b*.

The fan-shaft B is mounted in projecting ears *c c* in the thimble C, so as to give it a free rocking or oscillating motion, and one of the thimbles C has attached to it the box or casing G, which contains the spring-motor. 60 The latter consists essentially of a train of wheels, H, actuated by an ordinary spring and spring-barrel, through which a rotary motion is communicated to the disk I, which projects outside of the motor-box. In the face 65 of disk I is affixed adjustably a wrist-pin, K, in which is pivoted the pitman L. In the outer end of this is hinged a screw-bolt, M, which is inserted through an aperture in the end of shaft B contiguous to the motor. 70

On screw M work two nuts, *m m*, one on each side of the shaft, by means of which the screw may be adjusted relative to shaft B, through which it is inserted. It follows that by adjusting screw M up or down (which may readily be effected while the apparatus is in motion) the throw of pitman L and of the shaft may be regulated, thus regulating the arc of vibration of the fans F. 75

Having thus described my invention, I claim 80 and desire to secure by Letters Patent of the United States—

1. The combination of the standards A A, having bottom supports, *aa*, adjustable sleeves C C, having ears *c c* and set-screws D D, 85 rock-shaft B, perforated at one end, screw-bolt M, inserted through the perforated rock-shaft, and provided with the adjusting-nuts *m m*, motor H, incased in a box contiguous to and forming part of one of the adjustable 90 sleeves C, disk I, having adjustable wrist-pin K, and pitman L, connecting said wrist-pin and the screw-bolt M, all constructed and combined to operate substantially as and for the purpose herein shown and set forth. 95

2. The combination of the oscillating fan-shaft B, sleeves E, each having a socket, E', and pair of set-screws, *e* and *f*, and fans F, having shafts or handles F', provided with universal joints *i*, having set-screws *b*, substantially as and for the purpose herein shown and specified. 100

In testimony that I claim the foregoing as my own I have hereunto affixed my signature in presence of two witnesses.

GEORGE WHITFIELD OVERALL.
